PORABLE STORAGE CONTAINER FOR BULK ITEMS OR THE LIKE

Alan R. Cripe, 4511 Menokin Road,
Chesterfield County, Va.

Filed Feb. 3, 1964, Ser. No. 78,490

Term of patent 14 years

(Cl. D58—12.6)

FIG.-1

FIGURE 1 is a front perspective view of a portable storage container for bulk items or the like, showing my new design;

I claim:

The ornamental design for a portable storage container for bulk items or the like, as shown.
